UNDECYLENIC ACID AND UNDECYLENATE
ANTIMYCOTIC COMPOSITION

John C. Baker, Montclair, N. J., assignor to Wallace & Tiernan Products, Inc., Belleville, N. J., a corporation of New Jersey

No Drawing. Application April 21, 1945,
Serial No. 589,698

24 Claims. (Cl. 167—58)

1

The present invention relates to an antimycotic composition useful in the treatment of superficial fungus infection of humans and higher animals.

A great deal of research work has been done in the past looking toward the preparation of suitable therapeutic antimycotic compositions for the treatment of this type of infection, which is very common among large numbers of people, and is also at times a serious detriment to the personnel in our Armed Forces.

In the past, various materials have been suggested and many actually used for the treatment of this type of infection, including, for example, boric acid, salicylic acid, and sulfur (powder). It has been suggested to use both saturated and unsaturated fatty acids with various numbers of carbon atoms. Zinc salts have also been independently suggested for use (see Patent No. 2,190,714) wherein salts of saturated acids from 3 to 12 carbon atoms are disclosed and wherein zinc salts are also disclosed. Propionic acid has also been mentioned as a fungistatic agent. In view of the fact that this infection is quite difficult to control and as certain cases respond better to some treatments than to others; and conversely, as various of those materials above referred to have better effects on some persons than on others, there is still a substantial need in the treatment of this type of infection for additional and more effective materials, or combinations thereof in the treatment of many cases of infections of this type. In general, the results obtained by previously available materials are often unsatisfactory and seldom completely satisfactory.

Among the objects of the present invention, therefore, are to provide a more satisfactory therapeutic composition for the treatment of fungus infections of the type referred to, which will give superior results as contrasted with previously available materials and in some instances which will give positively desirable results in cases where the previously available materials would not give satisfactory results.

A more specific object of this invention is to provide an antimycotic preparation, which is compatible with the normal function of the skin, which produces no irritating effects upon the skin, even when used in large quantities; and yet which produces a powerful antimycotic action.

A further detailed object of the present invention is to provide a preparation or composition, which contains an effective antimycotic

2

agent in sparingly soluble form from which it may be slowly liberated.

A further object of the present invention is to provide an antimycotic agent, which, at the same time, is a good drying agent.

Another object of the present invention is to provide an antimycotic agent having physical properties which make it suitable for use as a dermatologic dusting powder and which also may be prepared in the form of an ointment without the addition of another solid phase.

One of the well recognized problems in therapeutics is to provide a therapeutic agent in such form that a high concentration of the agent is

never present in or on the body and yet which provides an even or stationary release of the active agent. This is of particular importance in the case of agents applied to the skin as this organ is very sensitive. It responds to irritat-

ing stimuli with an inflammatory type of reaction, which may in some instances be harmful and may counteract the beneficial effects of the therapeutic agent. Applying this principle to the present situation, it has been known for a

long time that the inert fatty acids have considerable antimycotic properties, yet heretofore these compounds have not been widely used for the treatment of fungus infections of the skin, for the reason, possibly among others, that if these

substances are administered in water soluble form by which they might produce a local high concentration on the skin, they may be somewhat irritating thereto. If water soluble salts of these fatty acids are used, they may in some cases, be irritating because of the production of an alkaline

reaction; while if the free fatty acids are used, they may in some cases, cause irritation because of an undesired increase in the hydrogen ion concentration; and finally, high concentrations of

both soluble acids and salts may be irritating because of the surface-active characteristics of the compound itself.

While water insoluble agents are as a rule quite inactive or inert in aqueous media, I have discovered that the zinc salts of olefinic acids containing from 6 to 12 carbon atoms are active antimycotics, when tested by the usual methods on Sabouraud's agar and are also highly effective and not irritating when used therapeutically.

Zinc salts of olefinic acids have a tendency to form colloidal solutions and can be obtained in highly divided form. Thus they can be spread evenly on the skin. They have lubricating properties and adhere to the skin, which is highly desirable in producing uniform and sustained thera-

peutic action. Because of these properties, the zinc salts of olefinic acids are useful components of ointments or powders intended for the application to body surfaces and are one of the essential ingredients of the compositions in accordance with the present invention. Oozing body surfaces are benefited by the application of finely divided material which absorbs moisture. While there are other finely divided soft powders used and useable for this purpose, including the zinc salts of paraffinic acids, the zinc salts of olefinic acids in addition to their useful function as above set forth are quite satisfactory in this respect. The use thereof as an ingredient of a composition of the type herein set forth for the various reasons above set forth is a primary feature of the present invention.

The chemical and chemotherapeutic properties of olefinic acids are per se known, as is also the comparison of these properties with those of corresponding paraffinic acids. The differences of these properties may possibly tend to explain to some extent at least, the desirable therapeutic properties of the zinc salts of the olefinic acids. In particular I have found that they are so inert that they can be applied to the most sensitive parts of the human skin without causing any substantial irritation. This is especially the case if care is taken that substantially neutral salts of olefinic acids are used. The drying properties of these salts are also quite remarkable, which is a desirable characteristic in treating infections of this type. Acid and basic zinc salts of olefinic acids may also be prepared under properly selected conditions and are quite useful in certain embodiments of the invention.

The composition of the present invention may be briefly summarized as follows: (1) a zinc salt of an olefinic acid having 6 to 12 carbon atoms; (2) an olefinic acid having 6 to 12 carbon atoms; (3) in most, but not all instances, a pharmacologically essentially inert carrier suitable respectively for the preparation of the compound in powder and ointment forms; (4) a material, usually somewhat alkaline in character, for neutralizing the acid present to a desired extent and controlling the pH of the composition in most instances when it is made up in the form of an ointment or paste; and (5) optionally added materials which may be totally omitted or varied as hereinafter set forth. These various components and their particular requirements, limitations, scope and proportions will be hereinafter set forth.

I have found that for the reasons above set forth, one essential ingredient of the compositions in accordance with my present invention to be a zinc salt of an olefinic acid having 6 to 12 carbon atoms. In this connection an acid having 12 carbon atoms, viz. alpha beta dodecylenic acid ($\text{CH}_3[\text{CH}_2]_2\text{CH}:\text{CHCOOH}$) has been studied as representing one extreme and acids having 6 carbon atoms, viz. alpha beta hexenoic acid ($\text{CH}_3[\text{CH}_2]_2\text{CH}:\text{CHCOOH}$) and omega hexenoic acid ($\text{CH}_2:\text{CH}[\text{CH}_2]_3\text{COOH}$) have been studied as the other extreme. All are about equally successful; from which I assume that the acids having intermediate numbers of carbon atoms are similarly appropriate and further that the position of the double bond is largely, if not wholly, immaterial. This last is reinforced by the results of tests using acids having 11 carbon atoms (undecylenic acids) wherein in one case the double bond was in the alpha beta position and in another case, in the omega position. In a

present commercial form of compositions in accordance with the present invention an omega unsaturated undecylenic acid is employed. The acid selected in the making of the salt may be straight or branched chain. The straight chain acids have been discussed above. As examples of branched chain acids, I have studied the results obtained from the use of the following (all alpha beta unsaturated): alpha beta 4 ethyl

10 hexenoic acid

15 alpha beta 4 ethyl octenoic acid

and alpha beta pentenoic acid having a cyclohexyl group in the chain

From the above I have concluded that branched and straight chain compounds are both effective, although the straight chain compounds are preferred as they are substantially the more active; and that the presence of a saturated hydrocarbon ring group does not negative although it may vary to some extent the fungicidal activity of the compound. The proportions in which this ingredient is to be used, will be later more apparent from the particular compositions given in the examples, and is contemplated to be from an effective amount up to 60% or more. In this connection it has been found that when the composition is prepared in powder form, a substantially higher proportion of the zinc salt may be used than when an ointment is prepared. In making ointments, not over 60% of this material is presently contemplated. Specifically, I now prefer to use zinc undecylenate

as a particular and preferred embodiment of the invention, although I do not wish to be limited in this respect.

A second major and essential ingredient is an olefinic acid per se, which has from 6 to 12 carbon atoms. This acid is subject to the same limitations as the anion of the zinc salt above discussed and may be the same acid as the anion of the zinc salt used or another acid within the definition; viz. it may be straight or branched chain; and it may have its double bond at any place in the chain. The desired proportions of this ingredient are from about 0.2% to about 10% with a preferred proportion of about 5%. The 5% limit is presently contemplated as applying particularly to the powder form, while in ointments as much as 10% may be used. Specifically I contemplate the use of undecylenic acid as the preferred member of this class.

The third ingredient, which I consider as usually, but not always, essential in the compositions according to my invention, may be defined only as a class of materials and is particularly a pharmacologically, essentially inert carrier of any suitable kind, which may constitute the balance of the proportions, once the other active ingredients have been combined together in the desired proportions. In the powder form of the invention this inert carrier may, if desired, be wholly omitted.

When the composition of the invention is to be prepared in powder form, I may use such materials as talc, bentonite, diatomaceous earth, or

titania as this inert pulverulent ingredient or carrier.

When the composition is to be prepared for use as a therapeutic in ointment form, I may use any suitable ointment base such as a vanishing cream type of base including a water soluble, high molecular weight substance such as the natural gums, tragacanth or acacia, or synthetic materials such as those known commercially as "Carbowax," or methyl cellulose. I also contemplate the use of any desired mixture of natural and artificial or synthetic materials in this respect. I may also use desired amounts, with or in place of these other materials of such things as petrolatum, lanolin, cetyl alcohol and propylene glycol.

The pH control of the composition as a whole is often of major importance, as it has been found that compositions having a pH in one range may be more advantageous in treating a given patient than those having a pH in another range. For this reason I contemplate control of pH within rather wide limits, that is, from about 3 to about 9 as extreme limits, or for the usual cases from about 5 to about 8. However, I have found that a preferred form of the invention, which is useable in many instances, has even a closer pH control, preferably between 6 and 7.

In order to obtain a desired pH in the composition, I contemplate that I may add a strong or weak base to neutralize a desired amount of the free acid added as aforesaid and thus adjust the pH to a selected value. The base thus added is preferably one which will form with the acid added as aforesaid, a salt which will be water soluble. As a specific embodiment of this feature of the invention I contemplate the use of triethanolamine, which may be added to the composition, for example, to react with undecylenic acid, to form a salt thereof and in an amount to give a pH of about 6.5, although other desired values of pH may be attained by the use of appropriate different amounts of triethanolamine. I have found in this respect that the triethanolamine salt of the undecylenic acid is a fairly effective solvent for the other active ingredient, which is preferably used therewith, that is, zinc undecylenate. It will be understood, however, that in certain instances where a rather strongly alkaline composition is desired, I may even use such a strong base as sodium hydroxide.

There are certain other materials, which may be optionally added to the composition as set forth hereinabove for giving certain desired properties to the composition as a whole. One type of such added materials, which are contemplated in accordance with the present invention, is that known as anionic wetting agents including such materials as sodium tetradecyl sulphate, sodium dioctyl sulfo-succinate and commercial materials known under the trade names of "Areskleene," "Areskap," "Aresket," "Duponol," "Nekal," and many others.

Also included in the possible variants of the composition are materials such as have heretofore been known and/or used in the treatment of infection, of this kind, such, for example, as boric acid, salicylic acid, benzoic acid, sulfur (powder) and certain at least of the paraffinic acids.

In the ointment form of the invention a certain proportion of water may, if desired, be in-

cluded, which may assist in bringing the composition to a desired consistency.

The following examples of various useful compositions in accordance with the present invention will illustrate how the various ingredients may be combined together in accordance with the principles hereinabove set forth and to attain desired results, it being understood that certain of the compositions may be more desirable in treating certain individual cases than are others.

Example #1 (powder)

20 parts by weight of zinc undecylenate is dispersed with 2 parts of undecylenic acid in an alcohol solution. The alcohol is evaporated and the powder which is obtained is mixed with 78 parts of talc until a uniform product results. This mixture is my present preferred form as a powder and is an antimycotic composition, which has been found useful in the treatment of mycotic infections of the foot.

Example #2 (powder)

15 parts by weight of zinc undecylenate and 10 parts of acid zinc undecylenate are mixed with 20 parts of zinc stearate and 55 parts of talc until a uniform product is obtained.

Example #3 (powder)

30 An example of a powder having a high content of zinc undecylenate and complementary low content of undecylenic acid is

	Percent
Zinc undecylenate	99.5
Undecylenic acid	0.5

Example #4 (ointment)

10 parts by weight of cetyl alcohol, 3 parts each of white petrolatum and lanolin are weighed into 40 a suitable container and melted by heating to 60° C. They are mixed until a uniform product is obtained. In a separate container 10 parts of propylene glycol and 40 parts of water are mixed and heated to 55° to 60° C. The two mixtures 45 are blended. 5 parts of undecylenic acid and enough triethanolamine is added to bring the pH up to 6.5. 0.5 parts of sodium tetradecyl sulfate are dissolved in benzol and added to a mixture of 20 parts zinc undecylenate. The benzol is 50 evaporated and the powder dried. The dry powder is added to the molten mixture of other ingredients and stirred. A soft three phase emulsion type of ointment results which has some of the characteristics of a vanishing cream. Sufficient water is then added and mixed until a uniform product of 100 parts by weight is obtained.

This composition may be summarized as follows:

	Per cent
Undecylenic acid	5
Zinc undecylenate	20
Sodium tetradecyl sulfate	0.5
Petrolatum	3
Lanolin	3
Cetyl alcohol	10
Propylene glycol	10
Triethanolamine to adjust the pH to 6.5 (2%).	
Water q. s.	

70 This formula represents my present preferred form of ointment, but I further contemplate that the amount of petrolatum, lanolin, cetyl alcohol, propylene glycol and water may be varied within reasonable limits as will be apparent to those skilled in the art and still yield a product having

7

a desired consistency. Zinc undecylenate may be varied from 10 to 20% and the sodium tetradecyl sulfate (wetting agent) from 0.1 to 1% without substantially varying the above composition. Similarly the undecylenic acid may vary from 2 to 10% and the triethanolamine may vary correspondingly to maintain the pH between 6 and 7 without substantially changing the above composition from that presently preferred as an ointment.

Example #5 (showing a variant of the ointment with a high undecylenic acid content)

	Per cent
Undecylenic acid	10
Zinc undecylenate	20
Sodium tetradecyl sulfate	0.5
Petrolatum	3
Lanolin	3
Cetyl alcohol	10
Propylene glycol	5
Triethanolamine sufficient to adjust pH to 6.5 (4%).	
Water q. s.	

Example #6 (illustrating a low concentration of undecylenic acid or the acid ingredient)

	Per cent
Undecylenic acid	0.2
Zinc undecylenate	20
Sodium tetradecyl sulfate	0.5
Stearic acid	5
Petrolatum	3
Lanolin	3
Cetyl alcohol	10
Propylene glycol	10
Triethanolamine sufficient to adjust pH to 6.5 (1.5 to 2%).	
Water q. s.	

Example #7 (ointment)

An example of an ointment having a high content of zinc undecylenate is

	Per cent
Undecylenic acid	5
Zinc undecylenate	60
Propylene glycol	10
"Carbowax 1500"	10
Triethanolamine	3
Water	12

Example #8 (illustrating a highly alkaline composition)

	Per cent
Undecylenic acid	5
Zinc undecylenate	18
Sodium tetradecyl sulfate	0.5
Petrolatum	3
Lanolin	3
Cetyl alcohol	10
Propylene glycol	10
Sodium hydroxide sufficient to adjust pH to 9 (1%).	
Water q. s.	

Example #9 (illustrating a composition where the anion of the zinc salt is different from the acid per se used)

	Per cent
Undecylenic acid	5
Zinc salt of alpha beta 4 ethyl hexenoic acid	18
Propylene glycol	10
"Carbowax 1500"	19
"Carbowax 4000"	30
Triethanolamine sufficient to adjust pH to 8.5 (3%).	
Water q. s.	

8

Example #10 (illustrating different acid anions and a low extreme of pH. This ointment has a pH of approximately 3)

	Per cent
Alpha beta hexenoic acid	10
Zinc undecylenate	18
Propylene glycol	10
"Carbowax 1500"	21
"Carbowax 4000"	30
Water q. s.	

Example #11 (illustrating different acid anions and without water present)

	Per cent
Undecylenic acid	5
Zinc nonenoate	13
Propylene glycol	22
"Carbowax 1500"	55
Methocel 15 c. p. s.	2
Triethanolamine	3

Example #12 (a powder form of the invention with a relatively high concentration of undecylenic acid)

	Per cent
Undecylenic acid	5
Zinc undecylenate	20
Diatomaceous earth	20
Talc	55

Example #13 (similar to Example #12 but with a low concentration of undecylenic acid)

	Per cent
Undecylenic acid	0.2
Zinc undecylenate	50
Talc q. s.	

40 Certain of the above examples illustrating extremes in concentrations of one or another of the ingredients or characteristics, are not as desirable for average use as some intermediate examples given, but have positive utility and may be especially desirable in treating certain cases, even to a greater extent than the intermediate compositions, which are usually preferred.

From the above examples, it will be seen that the various ingredients may be varied within the teachings hereinabove set forth for making both the powder and ointment forms of the invention. These examples further illustrate the extremes of variations of most of the ingredients and characteristics, particularly the essential ingredients and the essential characteristics such as pH.

55 While it is contemplated that the preferred forms of the invention as hereinabove set forth will be useful in treating average cases, it is specifically contemplated that certain of the more extreme compositions may have peculiar utility in certain individual cases. I do not wish to be limited, therefore, except by the scope of the appended claims, which are to be construed validly as broadly as the state of the prior art permits.

60 What is claimed is:

1. An antimycotic composition, prepared for use as a therapeutic, comprising a zinc salt of an olefinic acid having from 6 to 12 carbon atoms, and an olefinic acid having from 6 to 12 carbon atoms, said second named acid being substantially more readily soluble in use than said zinc salt.

2. An antimycotic composition in accordance with claim 1, wherein said zinc salt is zinc undecylenate.

3. An antimycotic composition in accordance with claim 1, wherein the second named olefinic acid is undecylenic acid.

75 4. An antimycotic composition, prepared for

use as a therapeutic, comprising zinc undecylenate, and undecylenic acid, said acid being substantially more readily soluble in use than said zinc undecylenate.

5. An antimycotic composition in accordance with claim 1, wherein the second named olefinic acid is a straight chain compound.

6. An antimycotic composition in accordance with claim 1, wherein said zinc salt is one of a straight chain olefinic acid, and wherein the second named olefinic acid is a straight chain acid.

7. An antimycotic composition in accordance with claim 1, wherein the olefinic acid radical of the zinc salt is the same as the acid radical of said olefinic acid.

8. An antimycotic composition, prepared for use in powdered form as a therapeutic, comprising a zinc salt of an olefinic acid having from 6 to 12 carbon atoms, an olefinic acid having from 6 to 12 carbon atoms, and a pulverulent pharmacologically essentially inert carrier material, said second named acid being substantially more readily soluble in use than said zinc salt.

9. An antimycotic composition in accordance with claim 8, wherein said pulverulent pharmacologically inert carrier material includes at least a substantial proportion of powdered talc.

10. An antimycotic composition, prepared for use in powder form as a therapeutic, comprising zinc undecylenate, undecylenic acid not over about 5%, and the balance a pulverulent pharmacologically essentially inert carrier material, said acid being substantially more readily soluble in use than said zinc undecylenate.

11. An antimycotic composition, prepared for use in a powder form as a therapeutic, comprising about 20% zinc undecylenate, about 2% undecylenic acid, and about 78% talc, said acid being substantially more readily soluble in use than said zinc undecylenate.

12. An antimycotic composition, prepared for use in ointment form as a therapeutic, comprising not over 60% of a zinc salt of an olefinic acid having from 6 to 12 carbon atoms, an olefinic acid having from 6 to 12 carbon atoms, and an alkaline material for reaction at least in part with said acid in an amount necessary to adjust the pH of the composition to a selected value from about 3 to about 9, said at least partly neutralized acid being substantially more readily soluble in use than said zinc salt.

13. An antimycotic composition prepared for use in ointment form as a therapeutic, comprising from an effective amount to about 60% of a zinc salt of an olefinic acid having from 6 to 12 carbon atoms, from about 0.2% to about 10% of an olefinic acid having from 6 to 12 carbon atoms, and a base of a type and present in an amount such as to neutralize said acid at least in part and to form therewith a water soluble salt, said base serving to predetermine the pH of the composition as a whole at a value from about 3 to about 9, said at least partly neutralized acid, in the form of said water soluble salt, being substantially more readily soluble in use than said zinc salt.

14. An antimycotic composition in accordance with claim 12, wherein the pH of the composition is predetermined at a value from about 5 to about 8.

15. An antimycotic composition, prepared for use in ointment form as a therapeutic, comprising not over about 60% of a zinc salt of an olefinic acid having from 6 to 12 carbon atoms, and an olefinic acid having from 6 to 12 carbon atoms.

said composition having a pH between about 3 and about 9, said second named acid being substantially more readily soluble in use than said zinc salt.

5. 16. An antimycotic composition, prepared for use in ointment form as a therapeutic, comprising as an active ingredient, zinc undecylenate dissolved at least in part in the triethanolamine salt of undecylenic acid, said composition having a pH from about 5 to about 8, said triethanolamine salt being substantially more readily soluble in use than zinc undecylenate.

17. An antimycotic composition, prepared for use in ointment form as a therapeutic, comprising from an effective amount to about 60% of a zinc salt of an olefinic acid having from 6 to 12 carbon atoms, from about 0.2% to about 10% of an olefinic acid having from 6 to 12 carbon atoms, an ointment base which is pharmacologically essentially inert, and a base for neutralizing at least a part of the acid ingredient and adjusting the pH to a desired value from about 3 to about 9, said at least partly neutralized acid ingredient being substantially more readily soluble in use than said zinc salt.
